(21) Appl. No.: **29/427,028**

CLAIM

(22) Filed: **Jul. 12, 2012**

The ornamental design for a combined melon baller and fruit scoop set, as shown and described.

(51) LOC (9) Cl. **07-02**

DESCRIPTION

(52) U.S. Cl.

USPC **D7/691**

(58) **Field of Classification Search** D7/691,

FIG. 1 is a perspective view for a combined melon baller and fruit scoop set, showing my new design;

D7/644, 368, 669, 688; 37/307, 341, 279;

FIG. 2 is a front view thereof;

7/110; 310/46.2; D24/122; 73/426; 206/499;

FIG. 3 is a top plan view thereof;

219/227

FIG. 4 is a rear view thereof;

See application file for complete search history.

FIG. 5 is a bottom plan view thereof;
